(57) **CLAIM**

The ornamental design for a street lamp, as shown and described.

DESCRIPTION

FIG. 1 is a perspective view of a street lamp of the present invention.

FIG. 2 is a front view of the street lamp of FIG. 1.

FIG. 3 is a rear view of the street lamp of FIG. 1.

FIG. 4 is a left side view of the street lamp of FIG. 1.

FIG. 5 is a right side view of the street lamp of FIG. 1.

FIG. 6 is a top view of the street lamp of FIG. 1.

FIG. 7 is a bottom view of the street lamp of FIG. 1.

FIG. 8 is another bottom view of the street lamp of FIG. 1 showing light emitting diodes that are visible when the lamp is in use.

FIG. 9 is another perspective view of the street lamp of FIG. 1 showing the design mounted on a light post.

FIG. 10 is an elevation view of the street lamp of FIG. 1 showing the design in an alternate position mounted on a light post; and,

FIG. 11 is an enlarged reference view of a portion of the wing of the street lamp of FIG. 1.

The broken lines shown on the drawings depict portions of the street lamp that form no part of the claimed design.
